TELEPHONE INSTRUMENT

Rudolph Frank Stehlík, Antwerp, Belgium, assignor to Associated Telephone & Telegraph Company, Chicago, Ill., a corporation of Delaware

Application May 11, 1939, Serial No. 272,951
In Great Britain May 18, 1938

2 Claims. (Cl. 179—103)

The present invention relates to telephone instruments and more particularly telephone handsets of the kind adapted to be employed in circumstances in which, though normally use can be made of the ordinary microphone transmitter, at times this is difficult or impossible. Such instruments are particularly advantageous for military purposes or as portable telephones for use in places where a great deal of noise is experienced in certain circumstances, or in conditions when it is inconvenient to put a microphone transmitter to the mouth, for instance when wearing a gas mask.

In such circumstances it is known to provide a throat transmitter or so-called laryngaphone in addition to the normal telephone instrument. This has usually been provided as a separate unit which can be strapped around the neck and connected by a cord to the terminals of the instrument which incorporates a switching device permitting the cutting out of the handset transmitter and the switching-in of the laryngaphone. This arrangement has certain disadvantages as if it is necessary to listen as well as to speak, the receiver of the handset must still be held to the ear. Moreover the separate unit with straps and cord is awkward to handle and store and under certain conditions the cord and strap are liable to become tangled and furthermore a switch has to be provided on the instrument and an extra operation is necessary to render the laryngaphone effective. The chief object of the present invention is to provide a neat and compact combined telephone and laryngaphone unit whereby the above difficulties are avoided.

According to one feature of the invention in a telephone handset a unit including a receiver and microphone of ordinary type is provided with a socket for the plugging in of a throat-operated microphone.

According to another feature of the invention in a telephone handset a unit including a receiver and microphone of ordinary type is provided with facilities for plugging in a throat-operated microphone in substitution for the ordinary microphone.

The invention will be better understood from the following description of one method of carrying it into effect which should be taken in conjunction with the accompanying drawing 50 comprising Figs. 1-4. Of these,

Fig. 1 shows the normal handset,

Fig. 2 shows the plug-in portion comprising the laryngaphone,

Fig. 3 is a fragmentary view showing the laryn-

gaphone in plugged-in position and indicating the contact operation produced thereby, while Fig. 4 represents a suitable circuit diagram.

It will be seen that the handset comprises the 5 usual receiver 1 and microphone transmitter 2 joined by the handle 3 which is split longitudinally and provided with the switching key 4 for connecting up the talking battery. The handle also includes the socket 5 adapted to receive the laryngaphone of Fig. 2.

This comprises essentially the member 6 which 10 is pressed against the throat to receive the speech vibrations and the plug portion 7 which fits into the socket 5 and makes the necessary electrical connections. As will be seen from Fig. 3 the plug spring 7 engages the spring 8 and moves it out of contact with the spring 9 thereby breaking the connection to the ordinary microphone and connecting up the laryngaphone in its place.

15 It will be seen from the circuit diagram of Fig. 4 that the complete instrument includes a magneto 10 with the usual switching springs 11 and control contacts 12, a bell 13, induction coil 14, buzzer 15, signalling key 17, and battery 18. 20 These are connected in a more or less conventional manner to the terminals 19 and 20 extending to the line.

The laryngaphone element is conveniently 25 housed in a casing of moulded material but metal or rubber may also be used if found more convenient. Moreover though in the system shown the plugging-in of the unit disconnects the ordinary microphone this is not essential and it might be thought desirable in some cases for both 30 to remain connected up. It will be seen that the pin connections are sufficiently long and robust for the laryngaphone to be held firmly in position after it has been plugged in. Its rigidity is increased by the fact that it secures a bearing 35 against the projection 21 on the mouthpiece 2. It will be seen also that the shape and location 40 of the unit are such that when it is plugged in the handset can be used with comparatively little change in position.

45 According to the invention therefore a very simple construction has been devised whereby a normal handset can be readily adapted to operation with a throat microphone with the minimum of additional equipment and the utmost convenience.

I claim:

1. A telephone handset unit having a handle carrying the usual transmitter and receiver thereon, a throat operated microphone having a

casing terminating in a plug rigid therewith, a socket in the handset, said socket containing switching springs operated for substituting the throat operated microphone for the usual transmitter when the plug is inserted in the socket and means cooperating with said socket for holding the microphone rigid with the unit above the transmitter.

2. In a telephone handset a handle carrying a transmitter on one end and a receiver on the 10

other end, a laryngaphone having a plug extension rigid therewith, a socket in the handle between the transmitter and receiver and adjacent the transmitter, a built out projection on the transmitter adjacent the socket, said projection and said socket cooperating to hold the laryngaphone rigidly supported on the handle above the transmitter when the plug is inserted in the socket.

RUDOLPH FRANK STEHLIK.
